JOSEPH SCHWEISS AND GEORGE R. ERICSON, OF ST. LOUIS, MISSOURI, ASSIGNEES TO
CARTER CARBURETOR CORPORATION, OF ST. LOUIS, MISSOURI, A CORPORATION
OF DELAWARE

CARBURETOR

Application filed February 23, 1929. Serial No. 342,060.

This invention relates to carburetors and particularly to devices for producing a temporary enrichment of the mixture delivered by the carburetor.

5 In certain types of carburetors for internal combustion engines, it is customary to provide a small pump connected to the throttle operating means in such a manner as to discharge a jet of fuel into the mixing chamber 10 when the throttle is opened. The jet through which this pump discharges is entirely separate and distinct from the main fuel supply means of the carburetor. The arrangement serves not only as a means of temporarily enriching the mixture upon acceleration of the 15 engine, but as a means of priming the engine before starting.

During operation, when the temperature is low, it is desirable to squirt the additional 20 fuel high into the air stream so that a large part of it will be vaporized by the contact with the air, and to secure the most perfect vaporization, the jet is directed so that the larger drops will impinge on the hot spot or other 25 warm portions of the intake manifold, so that they will be vaporized by the heat thereof. As the temperature rises, it becomes less desirable to squirt the supplementary jet into the air stream and onto the surface of the 30 intake manifold, and under certain conditions serious interference with the operation of the motor may result from such an arrangement.

It is an object of this invention to provide 35 means to deflect the jet of fuel delivered by the accelerating pump at high temperatures in such a manner that it will not be directed into the most rapidly moving part of the air stream and will not impinge on the hot surfaces of the manifold.

Another object of the invention is to provide 45 means automatically operable at high temperatures to prevent the over-enrichment of the fuel mixture by the accelerating pump without in any way affecting the operation of the pump itself.

It is another object of the invention to provide 50 means automatically operable at high temperatures to distribute the charge of fuel delivered by the accelerating pump over a

longer period whereby the over-enrichment of the mixture is prevented and the temporary increase of power is prolonged. Other objects will appear from the following description and the accompanying drawings, 55 referring to which:

Figure 1 is a somewhat diagrammatic cross sectional view of a carburetor embodying our invention.

Figure 2 is a side elevation of the carburetor shown in Figure 1.

Figure 3 is a side view of one form of thermally operated deflector.

Figure 4 is an end view of the deflector shown in Figure 2.

The reference numeral 1 designates a main body member having a passageway 2 terminating in a flange 3 which is adapted to be secured to the intake manifold of an internal combustion engine, the manifold being indicated at 4. A butterfly valve 5 of conventional construction is mounted on a shaft 6 and serves to control the flow of mixture through the passageway 2. A suitable lever 7 is provided for operating the throttle shaft. Also mounted on the shaft 6 is a crank 8 which is pivoted at 9 to the oscillating piston 10 of the accelerating pump 11. The carburetor is supplied with air from the usual air horn 12. The chamber 13 provides a passage for the air to the throat of the venturi 14 and into the mixing chamber 15 where it is mixed with fuel before passing through the throttle valve and the outlet conduit 2. The fuel is supplied by conventional means through the inlet nipple 16, which is secured to the body member 1 and communicates with the inlet side of the float valve 17, the movement of this valve being controlled in a well known manner by the float 19 which is carried in the float chamber 18. When the fuel level in the fuel bowl or float chamber falls below the line A—A, the valve 17 is permitted to open, allowing fuel to enter and fill the bowl up to the proper level. When this level is reached, the float rises and closes the valve.

It will be seen that the fuel level A—A is such as to normally maintain a quantity of fuel in the depression or accelerating well 40

at the lower part of the chamber 13. This fuel accumulates in the accelerating well during low speed operation and is picked up by an increase in the speed of the air stream, such as would occur when the throttle is suddenly opened, thereby giving an additional quantity of fuel for acceleration.

The tube 20 is connected to the float chamber at a point below the fuel level to provide a main fuel supply. The accelerating pump 11 communicates with the conduit 21, the inlet valve 22, and the outlet passage 23; an inwardly opening check valve 24 is seated against the inlet 22, as shown, thus forming an inlet check valve for the pump. The passage 23 is provided with a shoulder 25 upon which is seated a ball check 26 forming an outlet check valve for the pump. A suitable jet nozzle 27 is secured to the upper end of the bore 23 and serves to retain the ball check 26 in position as well as to form the discharge nozzle for the accelerating pump.

The body of the carburetor is provided with a bore 28 to receive a substantially cylindrical plug 29, and a set screw 30 is provided to releasably hold the plug 29 in position. The upper end of the plug is provided with a screw driver slot 31 which serves to adjust the plug and to indicate its position. The inner and opposite end of the plug is slotted to receive a strip of bimetallic thermally responsive metal 32 which extends downwardly and toward the line of discharge D of the jet 27. Upturned lugs or baffles 33 are attached to the strip 32 and are preferably formed in the manner shown to a diameter not greater than that of the bore 28 so that they can be readily withdrawn or inserted with the strip through the bore 28. The lugs are attached to the thermostatic strip by a rivet at the lower end only, so that the bending of the strip under the influence of temperature changes will not be interfered with by the stiffness of the flanges.

The strip 32 comprises a strip of metal 34 having a low coefficient of expansion attached to another strip of metal 35 having a high coefficient of expansion.

The operation of the device is as follows: When the carburetor is in operation, suction in the manifold 4 draws air through the air horn 12, the chamber 13, and the venturi 14. The reduction of pressure at the throat of the venturi draws fuel from the tube 20 and causes it to be sprayed into the mixing chamber 15. The throttle 5 controls the passage of mixture from the mixing chamber into the manifold. When the throttle valve is moved toward closed position, the piston 10 is moved upwardly in the pump 11, drawing fuel through the inlet 22 past the ball check 24 and into the pump.

When it is desired to accelerate the engine, the throttle is opened causing the crank 8 to move the piston 10 downwardly in the pump,

thereby forcing fuel through the conduits 21 and 23 past the ball check 26 and through the jet 27. When the temperature is low, the strip 32 is bent to the right of the observer, as shown by the full lines in Figure 1, and the jet of fuel passes up through the throttle valve along with the air stream and impinges on the walls of the passage 2 and the manifold 4. A considerable part of the fuel is, of course, vaporized and carried along with the air stream of the engine. That which strikes the walls of the conduit is vaporized more slowly and is eventually picked up by the air stream and carried into the engine.

As the temperature rises, the drops of fuel which impinge on the walls of the passage-way are vaporized more quickly, resulting in a sudden over-enrichment of the mixture upon operation of the pump, and insufficient duration of time during which the additional fuel is supplied. Under these conditions, the increased temperature bends the strip 32 to the left, as shown in Figure 1, and intercepts a portion or all of the jet, causing the fuel to be deflected against the wall of the chamber 13 below the venturi.

The rate of flow of air in this part of the carburetor is lower than the rate of flow through the venturi, the outlet passage 5, and the intake manifold 4; and for this reason the deflected fuel is vaporized more slowly than if it had been squirted directly through the throat of the venturi and the most rapidly moving part of the air stream onto the warm surfaces over which air is passing at a relatively high speed.

The fuel will, however, eventually be picked up by the air passing through the chamber 13 and carried into the engine. It is also quite likely that the walls of the chamber 13 will be cooler than the walls of the conduit 2 and the intake manifold 4, and for this reason also the slower vaporization will occur. By this arrangement, the interval during which the enriched mixture is supplied is lengthened while the temporary supply of over-rich mixture is avoided.

It will be seen that we have provided a simple, reliable, and easily manufactured device for the purpose described, and that the invention may be embodied in various ways. Accordingly, we do not wish to be limited, except as set forth in the following claims.

We claim:

1. In a carburetor, a mixing conduit, a main fuel supply tube connected to said conduit to normally supply fuel thereto, a valve for controlling the passage of mixture through said conduit, an auxiliary fuel supply nozzle, means for discharging a jet of auxiliary fuel through said nozzle upon a movement of said throttle, a baffle, and thermally operable means to move said baffle into the path of said jet when temperature rises.

2. In a carburetor, a mixing conduit, an

accelerating pump adapted to discharge a jet of fuel into said conduit, a baffle normally out of the path of said jet, and thermally operated means for moving said baffle into the discharge jet of said pump when the temperature is high.

3. In a carburetor, a mixing conduit, an accelerating pump having a discharge jet directed toward the most restricted part of said conduit, and automatic means operable upon an increase in temperature for deflecting said jet into a less restricted part of said conduit.

4. In a carburetor, a mixing conduit adapted to convey an air stream, an accelerating pump having a discharge jet arranged to discharge fuel into a rapidly moving part of said air stream, and means operable at high temperature to deflect said jet into a slower moving part of said air stream.

5. In a carburetor, a mixing conduit adapted to convey an air stream, a pump having a discharge jet arranged to discharge fuel into a certain part of said conduit, and automatic means operated by temperature changes to cause said fuel to be discharged into a different part of said conduit.

6. In a carburetor, means forming a main conduit, an accelerating well in the lower portion of said conduit, an accelerating pump adapted to discharge into said conduit above said accelerating well, and means operated by temperature changes to deflect said discharge into said accelerating well.

7. In a carburetor, a mixture conduit, a fuel chamber, a main fuel supply means normally supplying fuel from said chamber to said conduit, a pump for supplying additional quantities of fuel to a certain part of said conduit, and thermally operated means for deflecting the additional quantities of fuel to another part of said conduit when the temperature is high.

8. In a carburetor, a fuel chamber, a mixture conduit, means normally supplying fuel from said fuel chamber to said mixture conduit, a valve for controlling the flow of fuel mixture through said conduit, means for controlling said valve, means operated by said controlling means for supplying additional quantities of fuel to a part of said conduit, and a deflector operable at high temperatures to deflect the additional fuel to another part of said conduit.

9. In a carburetor, a body member having a chamber therein, a passageway forming an outlet for said chamber, a manually operable valve controlling said passageway, a pump, a discharge nozzle for said pump mounted in the wall of said chamber, means for simultaneously operating said pump and said valve, and a thermally operated baffle in said chamber.

10. In a device of the class described, a cylindrical plug, a bimetallic strip secured at one end of said plug and extending there-

from in a substantially axial direction, a baffle member carried by said strip and attached thereto only at a point near the end of the strip opposite the plug, whereby flexing of said strip will not be interfered with by the stiffness of said baffle member.

11. In a device of the class described, a substantially cylindrical plug, a bimetallic strip attached to an end of said plug and extending in an axial direction therefrom, a flanged baffle carried by said strip, said plug, flange, and strip being insertable through a circular opening of the same diameter as said plug.

12. In a device of the class described, a substantially cylindrical plug, a bimetallic strip attached to an end of said plug and extending in an axial direction therefrom, a flanged baffle carried by said strip, said plug, flange, and strip being insertable in a circular opening of the same diameter as said plug and an eccentric screwdriver slot in the end of said plug opposite said strip for receiving an adjusting tool and for indicating the position of said baffle.

13. In a device of the class described, a conduit, means forming a conduit, a manually operable priming pump for discharging a jet of fuel into said conduit, a baffle adapted to be moved into or out of the path of said jet, and thermostatic means for moving said baffle.

14. In a carburetor, means forming a mixing conduit and a constant level fuel supply chamber, a main fuel nozzle discharging fuel from said constant level supply chamber into said mixing conduit, a pump having a fuel inlet from said constant level supply chamber, a check valve for controlling said inlet, said pump having a discharge nozzle for discharging fuel into said mixing conduit and heat controlled means for returning a portion of the fuel discharged by said pump towards said constant level supply chamber.

In testimony whereof we affix our signatures this 14th day of February, 1929.
